THOMAS J. KING, OF SEATTLE, WASHINGTON, ASSIGNOR TO KING AND WINGE SHIP-BUILDING COMPANY, OF SEATTLE, WASHINGTON, A CORPORATION OF WASHINGTON.

DESIGN FOR A STANDARD AND CASING FOR A WINDLASS.

54,268.

Specification for Design.

Patented Dec. 9, 1919.

Application filed June 30, 1919. Serial No. 307,860. Term of patent 14 years.

To all whom it may concern:

Be it known that I, THOMAS J. KING, a citizen of the United States, residing at Seattle, in the county of King and State of Washington, have invented a new, original, and ornamental Design for a Standard and Casing for a Windlass, of which the following is a specification, reference being had to the accompanying drawings, forming part thereof.

Figure 1 is an end elevational view of a standard and casing for a windlass showing my new design. Fig. 2 is a side elevation and Fig. 3 is a plan view of the same.

What I claim is:

The ornamental design for a standard and casing for a windlass, as shown.

THOMAS J. KING.
